CLAIM

The ornamental design for an aerodynamic device, as shown and described.

DESCRIPTION

FIG. 1 is a perspective view of the aerodynamic device.

FIG. 2 is a front view of the aerodynamic device.

FIG. 3 is a back view of the aerodynamic device.

FIG. 4 is a left side view of the aerodynamic device.

FIG. 5 is a right side view of the aerodynamic device.

FIG. 6 is a top view of the aerodynamic device.

FIG. 7 is a bottom view of the aerodynamic device.

FIG. 8 is an exploded view of the aerodynamic device.

FIG. 9 is a left side view of a single aerodynamic device for ease of illustration; and,

FIG. 10 is a right side view of a single aerodynamic device for ease of illustration.

The broken lines in FIGS. 1 through 8 define environmental structures and form no part of the claimed design.
